UNITED STATES PATENT OFFICE.

WALTER D'ARCY RYAN, OF SCHENECTADY, NEW YORK.

DESIGN FOR A VEHICLE HEADLIGHT HOUSING.

Application filed July 9, 1924. Serial No. 10,095. Term of patent 14 years.

To all whom it may concern:

Be it known that I, WALTER D'ARCY RYAN, a citizen of the United States, residing at Schenectady, in the county of Schenectady and State of New York, have invented a new, original, and ornamental Design for Vehicle Headlight Housing, of which the following is a specification, reference being had to the accompanying drawing, forming part thereof.

In the drawing:

Figure 1 is a perspective from the rear

and to one side of the headlamp of my design, and

Figure 2 is a front view and perspective of the headlamp as viewed from a position to one side.

I claim:

The ornamental design for a vehicle headlight housing as shown.

In witness whereof, I hereunto subscribe my name, this 25th day of June, 1924.

WALTER D'ARCY RYAN.
